[57] ABSTRACT

An article holder comprises a base, a bracket, a collar, and a cover. The base has a disk, a plurality of hollow posts and a fence disposed on the disk. A threaded socket is disposed on a center of the base. A threaded through hole is formed in the threaded socket. A plurality of slots are formed on the base. The bracket has an annular seat and a hollow mount disposed on two opposite ends of the bracket. A crossbar is disposed on the annular seat. A round hole is formed on a center of the crossbar. The annular seat is disposed on the disk to surround the fence. A collar is disposed on the annular seat. A cover is disposed on the collar. A threaded recess hole is formed on the cover. A plurality of studs fasten the disk on a wall via the corresponding slots. A bolt passes through the round hole and the threaded through hole. The threaded recess hole engages with a distal end of the bolt.

FIG. 1

FIG. 2

FIG. 3

FIG. 4

FIG. 5

ARTICLE HOLDER

BACKGROUND OF THE INVENTION

The invention relates to an article holder. More particularly, the invention relates to an article holder in a bathroom.

Most conventional article holders are adhered on walls. These article holders may be easily fallen down after holding heavy articles for a long period of time.

SUMMARY OF THE INVENTION

An object of the invention is to provide an article holder which can be fastened on a wall of a bathroom stably.

Accordingly, an article holder comprises a base, a bracket, a collar, and a cover. The base has a disk, a plurality of hollow posts disposed on the disk, and a fence disposed on the disk to surround the hollow posts. A threaded socket is disposed on a center of the base. A threaded through hole is formed in the threaded socket. A plurality of slots are formed on the base. The bracket has an annular seat disposed on a first end of the bracket and a hollow mount disposed on a second end of the bracket. A crossbar is disposed on the annular seat. A round hole is formed on a center of the crossbar. The annular seat is disposed on the disk to surround the fence. The collar is disposed on the annular seat. The cover is disposed on the collar. A threaded recess hole is formed on the cover. A plurality of studs fasten the disk on a wall via the corresponding slots. A bolt passes through the round hole and the threaded through hole. A nut screws on a distal portion of the bolt. The threaded recess hole engages with a distal end of the bolt.

According to the second embodiment, another article holder has a base, a bracket, a collar, and a cover. The collar is disposed on the bracket. The cover is disposed on the collar. The bracket has an elongated arm. Two hollow seats are formed in the elongated arm to receive two corresponding rods. A towel is hung on the rod.

According to the third embodiment, an article holder has a base, a bracket, a collar, and a cover. The collar is disposed on the bracket. The cover is disposed on the collar. A cup holder is disposed on a distal end of the bracket. A circular recess and a plurality of oblong holes are formed on the cup holder. The circular recess receives a cup. A toothbrush is inserted in the oblong hole.

According to the fourth embodiment, an article holder has a base, a bracket, a collar, and a cover. The collar is disposed on the bracket. The cover is disposed on the collar. An ashtray holder is disposed on the bracket. An annular hoop is disposed on a distal end of the ashtray holder to receive an ashtray.

According to the fifth embodiment, an article holder has a base, a bracket, a collar, and a cover. The collar is disposed on the bracket. The cover is disposed on the collar. A shortened arm is disposed on the bracket. A hollow sleeve is disposed on a distal end of the shortened arm. A loop is positioned by the hollow sleeve. A bath towel is hung on the loop.

According to the sixth embodiment, an article holder has a base, a bracket, a collar, and a cover. The collar is disposed on the bracket. The cover is disposed on the collar. A leg extends downward from the bracket. A clip mount is disposed beneath the leg. A panel is inserted through the clip mount. A screw fastens the panel and the clip mount together.

BRIEF DESCRIPTION OF THE DRAWINGS

FIGS. 1 to 3 are perspective exploded views of an article holder of a first preferred embodiment in accordance with the invention;

FIG. 2 is a sectional assembly view of FIG. 1;

FIG. 4 is a sectional assembly view of FIG. 2;

FIG. 5 is a perspective assembly view of an article holder of a second preferred embodiment in accordance with the invention;

FIG. 6 is a perspective assembly view of an article holder of a third preferred embodiment in accordance with the invention;

FIG. 7 is a perspective assembly view of an article holder of a fourth preferred embodiment in accordance with the invention;

FIG. 8 is a perspective assembly view of an article holder of a fifth preferred embodiment in accordance with the invention; and

FIG. 9 is a perspective assembly view of an article holder of a sixth preferred embodiment in accordance with the invention.

DETAILED DESCRIPTION OF THE INVENTION

Referring to FIGS. 1 and 2, an article holder 10 has a base 20, a bracket 30, a collar 40, and a cover 50. The base 20 has a disk 21, a plurality of hollow posts 241 disposed on the disk 21, and a fence 24 disposed on the disk 21 to surround the hollow posts 241. A threaded socket 23 is disposed on a center of the base 20. A threaded through hole 231 is formed in the threaded socket 23. A plurality of slots 22 are formed on the base 20. The bracket 30 has an annular seat 31 disposed on a first end of the bracket 30 and a hollow mount 33 disposed on a second end of the bracket 30. A crossbar 32 is disposed on the annular seat 31. A round hole 321 is formed on a center of the crossbar 32. The annular seat 31 is disposed on the disk 21 to surround the fence 24. The collar 40 is disposed on the annular seat 31. The cover 50 is disposed on the collar 40. A threaded recess hole 51 is formed on the cover 50. A plurality of studs 80 fasten the disk 21 on a wall W via the corresponding slots 22. A bolt 60 passes through the round hole 321 and the threaded through hole 231. A nut 70 screws on a distal portion of the bolt 60. The threaded recess hole 51 engages with a distal end of the bolt 60.

Referring to FIGS. 3 and 4, A threaded post 61 is disposed on the center of the disk 21 instead of the threaded socket 23 and the bolt 60. Therefore, the function of the threaded post 61 is the same as the function of the threaded socket 23 in addition to the bolt 60.

Referring to FIG. 5, another article holder 10a has a base 20a, a bracket 30a, a collar 40a, and a cover 50a. The collar 40a is disposed on the bracket 30a. The cover 50a is disposed on the collar 40a. The bracket 30a has an elongated arm 34a. Two hollow seats 341a are formed in the elongated arm 34a to receive two corresponding rods 342a. A towel 343a is hung on the rod 342a.

Referring to FIG. 6, a third article holder 10b has a base 20b, a bracket 30b, a collar 40b, and a cover 50b. The collar 40b is disposed on the bracket 30b. The cover 50b is disposed on the collar 40b. A cup holder 35b is disposed on a distal end of the bracket 30b. A circular recess 351b and a plurality of oblong holes 353b are formed on the cup holder 35b. The circular recess 351b receives a cup 352b. A toothbrush 354b is inserted in the oblong hole 353b.

Referring to FIG. 7, a fourth article holder 10c has a base 20c, a bracket 30c, a collar 40c, and a cover 50c. The collar 40c is disposed on the bracket 30c. The cover 50c is disposed on the collar 40c. An ashtray holder 36c is disposed

on the bracket 30c. An annular hoop 361c is disposed on a distal end of the ashtray holder 36c to receive an ashtray 362c.

Referring to FIG. 8, a fifth article holder 10d has a base 20d, a bracket 30d, a collar 40d, and a cover 50d. The collar 40d is disposed on the bracket 30d. The cover 50d is disposed on the collar 40d. A shortened arm 37d is disposed on the bracket 30d. A hollow sleeve 371d is disposed on a distal end of the shortened arm 37d. A loop 372d is positioned by the hollow sleeve 371d. A bath towel 373d is hung on the loop 372d.

Referring to FIG. 9, a sixth article holder 10e has a base 20e, a bracket 30e, a collar 40e, and a cover 50e. The collar 40e is disposed on the bracket 30e. The cover 50e is disposed on the collar 40e. A leg 38e extends downward from the bracket 30e. A clip mount 381e is disposed beneath the leg 38e. A panel 383e is inserted through the clip mount 381e. A screw 382e fastens the panel 383e and the clip mount 381e together.

The invention is not limited to the above embodiment but various modification thereof may be made. Further, various changes in form and detail may be made without departing from the scope of the invention.

I claim:

1. An article holder comprises:

a base, a bracket, a collar, and a cover,

5 the base having a disk, a plurality of hollow posts disposed on the disk, and a fence disposed on the disk to surround the hollow posts,

a threaded socket disposed on a center of the base,

10 a threaded through hole formed in the threaded socket, a plurality of slots formed on the base,

the bracket having an annular seat disposed on a first end of the bracket and a hollow mount disposed on a second end of the bracket,

15 a crossbar disposed on the annular seat,

a round hole formed on a center of the crossbar, the annular seat disposed on the disk to surround the fence,

the collar disposed on the annular seat,

20 the cover disposed on the collar,

a threaded recess hole formed on the cover,

25 a plurality of studs fastening the disk on a wall via the corresponding slots,

a bolt passing through the round hole and the threaded through hole,

the threaded recess hole engaging with a distal end of the bolt.
